UNITED STATES PATENT OFFICE.

HARRY C. LASSAM, OF LONDON, ENGLAND.

GLAZING-BAR FOR ROOFS, SKYLIGHTS, &c.

SPECIFICATION forming part of Letters Patent No. 545,237, dated August 27, 1895.

Application filed September 18, 1894. Serial No. 523,511. (No model.) Patented in England March 3, 1894, No. 4,492.

To all whom it may concern:

Be it known that I, HARRY C. LASSAM, a subject of the Queen of Great Britain, residing at 6 Kinver Road South, Sydenham, London, S. E., England, have invented certain new and useful Improvements in Glazing-Bars for Roofs, Skylights, &c., (for which I have obtained a patent in Great Britain, No. 4,492, dated March 3, 1894,) of which the following is a full, clear, and exact specification.

This invention relates to lead or other metallic glazing bars or strips for holding and securing glass to sash-bars, astragals, or iron or steel bars of commercial shapes in the construction of roofs, skylights, and similar structures.

The present invention has for its objects to simplify and improve the prior glazing-bars or glass-holding strips; to provide the glazing-bar with a novel expansion-joint for the glass; to render the glazing-bar susceptible of general application to ordinary wooden or metal sash-bars, astragals, or iron or steel bars of commercial shapes now in use or to be hereafter constructed; to avoid the necessity of specially constructing sash-bars or astragals for receiving the lead or composition glazing-bar; to provide a durable and simple construction which can be very economically manufactured; to provide a novel construction of expansion-joint flanges or wings which will prevent them from warping, while permitting expansion and contraction of the glasses; to provide a perfect dust and water tight expansion-joint in a glazing-bar or glass-holding strip of ductile metal which is so constructed and is provided with such means that it can be conveniently and economically applied to the upper surfaces of sash-bars, astragals, or iron or steel bars of commercial shapes that may be applicable and affords a substantial support for ladders or other rests used in repairing roofs or skylights, and to provide a novel, simple, and efficient glazing-bar or glass holding and attaching strip which can be drawn from lead or other ductile metal and be formed integral or in a single piece with an improved expansion-joint, a central core, and a flat or flattened base or body having side flanges to embrace and hug an ordinary sash-bar or any other ordinary sash-bar or steel or iron bar of com-

mercial shape having a plain top surface or surfaces.

To accomplish all these objects my invention involves the features of construction and the arrangement of parts hereinafter described and claimed, reference being made to the accompanying drawings, in which—

Figure 1 is a broken perspective view showing a portion of the improved glazing-bar, a portion of an ordinary metal sash-bar to which the glazing bar is applied, and portions of two glasses secured by the glazing-bar; and Fig. 2 is a similar view showing the improved glazing-bar applied to an ordinary wooden sash-bar.

In order to enable those skilled in the art to make and use my invention, I will now describe the same in detail, referring to the drawings, wherein—

The numeral 1 indicates the flat or flattened base or body of my improved glazing-bar. This bar, as a unit, is drawn from lead or ductile metal or composition of metal and is formed integral or in a single piece with the pendent longitudinal edge flanges 2, the longitudinal upwardly-projecting edge ribs 3, the central longitudinal solid core-piece or rib 4, and the two inclined wings 5, leading from the opposite sides of the solid core-piece or rib 4 and constituting the expansion-joint, as will more fully hereinafter appear. The base or body 1 is flat or flattened to fit snugly and squarely upon the flat upper surface 6 of a sash-bar 7, and the flanges 2 hang from the opposite longitudinal edges of the base or body, so that they can embrace and hug the sash-bar. If the sash-bar is composed of an ordinary angle-iron, such as a T-shaped iron, as in Fig. 1, the side flanges 2 can be bent under and pressed closely against the flanges 8 of the T-iron. If the sash-bar is of wood, as in Fig. 2, the flat base or body 1 rests squarely on the top flat surface 9 of the wooden sash-bar, while the flanges 2 embrace the bar and closely hug the parallel side surfaces 10 thereof and are fastened thereto by nails, screws, or other suitable means. The formation of the base or body with the pendent longitudinal edge flanges 2 enables the glazing-bar to be conveniently and firmly applied and secured on ordinary sash-bars, such as are now in use in roofs or skylights, which

is very advantageous over that class or type of glazing bars or strips requiring specially-constructed sash-bars which are segmentally-shaped in cross-section.

5 The longitudinal edge ribs 3 are substantially triangular in shape to facilitate drawing the same, and they rise above the top surface of the base or body sufficiently high to act as supports for the approximate edge portions of the glasses 12.

The inclined wings 5 extend from the core-piece or rib 4, and start therefrom at points below the top edges of the triangular glass-supporting ribs 3. The wings also extend approximately horizontal, as at 5^a, and these extensions are uniformly increased in thickness from their angles or corners 13 to their outer edges 14 for the purpose of effectually preventing warping of the metal due to heat or any other cause. The wings 5 stand at an angle to the core-piece or rib 4 to provide a space between the wings and core-piece or rib sufficient to permit the wings to move toward and from the core-piece or rib, so that when 25 the glasses 12 are in place, as shown, and the extensions 5^a are cemented to the edges of the glasses, if the latter expand or contract, the wings 5 can readily move or yield toward or from the core-piece or rib. By this means I 30 provide a dust and water tight expansion-joint in a glazing-bar having pendent flanges to embrace an ordinary sash-bar. It has heretofore been proposed to provide a lead glazing-strip with flanges to lap over the edges of the glasses and hold the latter down upon glass-supporting rests; but in such devices 35 the strip is made of a sheet of comparatively thin lead folded about the segmental head of a specially-constructed sash-bar. This is expensive, intricate in construction, difficult to

manufacture in a durable manner, and requires specially rolled or bent sash-bars, whereas my improved glazing bar or strip, with its expansion-joint wings all integral and in one piece, can be cheaply made by ramming 45 or drawing through a die in an ordinary lead-drawing machine. It is simple, easily manufactured, and is strong, durable, and applicable to ordinary sash-bars or steel or iron bars of ordinary commercial shapes or wooden as- 50 trags.

Having thus described my invention, what I claim is—

1. As an improved article of manufacture, a glazing-bar of ductile metal formed integral 55 with a base or body 1 having longitudinal, pendent flanges 2 at its edges for embracing an ordinary sash-bar or iron beam, longitudinal edge ribs 3, longitudinal, central core-piece 4, and inclined wings 5 extending from 60 the core-piece and movable to and from the latter to form an expansion joint, substantially as and for the purposes described.

2. A glazing-bar drawn in a single piece of ductile metal with the base 1, pendent side 65 flanges 2, upwardly projecting edge ribs 3, a central, vertical core-piece 4, and inclined wings 5 leading from opposite sides of the core-piece from points below the level of the upwardly-projecting edge-ribs and formed 70 with extensions 5^a which gradually increase in thickness toward their outer edges to prevent warping, said wings being movable toward and from the core-piece to form an expansion joint, substantially as and for the 75 purposes described.

H. C. LASSAM.
